HYDROMETER

George K. Porter, Philadelphia, Pa., assignor, by
mesne assignments, to American Instrument
Company, Silver Spring, Md., a copartnership
composed of William H. Reynolds and Leopold
Freedman

Application January 27, 1936, Serial No. 61,068

6 Claims. (Cl. 265—45)

This invention relates to hydrometers for measuring the density of liquids and, among other objects, aims to provide an improved hydrometer of the type having a glass ballast chamber fused to or integrally united with the lower end of the float chamber and so constructed that the stresses in the glass, caused by the fusing and sealing operations in the process of manufacture of the instrument, are distributed throughout the walls of the ballast chamber and will not cause the chamber to crack or break after the instrument is used for a period of time. The idea is to provide an elongated, bulbous, ballast chamber, secured intermediate its ends to the lower end of the float chamber so as to permit some expansion and contraction of the glass at the fused joint without cracking the float chamber.

Other aims and advantages of the invention will appear in the specification when considered in connection with one embodiment of the invention illustrated in the accompanying drawing, wherein:

Fig. 1 is an elevation disclosing a step in the preferred method of making the instrument;

Fig. 2 is a similar view showing another step, parts being shown in section;

Fig. 3 is a similar view showing the ballast chamber after it is formed or shaped;

Fig. 4 is a similar view showing the ballast chamber temporarily sealed off and the ballast placed in the float chamber ready for rough calibration of the instrument; and

Fig. 5 is an elevation of the completed instrument.

It has been found in practice that hydrometers having ballast chambers formed of glass and fused to the bottom of the float chamber, such as are shown in the patent to Hiegersell No. 1,610,616, are subject to cracking strains caused by the heat applied to the glass during the sealing, opening and resealing operations on the end of the ballast chamber. The heat of fusion in these operations is conducted to the joint at the end of the float chamber and a glass disk will prevent any relative expansion or contraction. It is impossible to anneal the joint after the usual mercury ballast is sealed in the ballast chamber. The present invention provides a greatly improved ballast chamber which permits sufficient expansion and contraction at the joint between it and the float chamber to prevent cracking. In fact, it provides a chamber in which the strains are reduced to a minimum because of an increased area of glass in the upper end of the

ballast chamber through which the stresses are distributed.

Referring particularly to the drawing, the instrument there shown for illustrative purposes has a bulbous ballast chamber in the form of a double cone, which is the preferred commercial design. Fig. 1 shows one of the first steps in the manufacture of an instrument of this type. In this instance, there is shown a cone 10 formed on one end of a glass tube 11 which is of the same diameter as the tube 12 which forms the cylindrical float chamber. This cone is formed in the usual manner by the ordinary glass blowing operations. It is then inserted in the open lower end of the float chamber tube 12 and fused to said tube to provide a fused joint 13 around the base of the cone. While the fused joint and the parts adjacent to it are still hot, the tube 11 below the end of the float chamber is drawn and shaped to form a bottom cone 14 having a tail 15, the waste portion of the tube 11 being broken off. Obviously, the double cone may be formed before it is joined to the float chamber, but the above described method is preferred. In this condition, the fused-on double cone is annealed in an oven to relieve the joint and the portions of the double cone and float chamber adjacent thereto of destructive cracking strains. An open stem 16 of the desired length is fused on the upper end of the float chamber in the usual manner.

The instrument is now ready to be roughly calibrated. This is done as shown in Fig. 4, by sealing off the ballast chamber. The lower end of the cone 14 is sealed in a flame and the tail 15 is pulled off; then, the mercury ballast 17 is introduced into the float chamber through the open stem. The weight of mercury is determined by adding it until the lower portion of the stem is submerged and the zero calibration is at the desired point on the stem. Then, the mercury is removed from the float chamber and introduced into the ballast chamber by reopening the ballast chamber in a flame and, then, resealing it by refusing the opening in the tip of the lower cone. The instrument is then completed by finally calibrating it and inserting the usual paper scale in the stem and, thereafter, sealing the upper end of the stem.

From the foregoing description, it will be observed that the ballast chamber is formed of a unitary mass of glass and there is only one fused joint at its junction with the float chamber. Moreover, the upper cone 10 within the float chamber presents a much greater glass area than

does an ordinary glass disk extending across the lower end of the float chamber to provide a partition, as in the aforesaid patent. It has been found in practice that instruments of this type 5 will stand a great deal more abuse than instruments made according to the aforesaid patent and that they do not crack or break due to any inherent strains or stresses induced in the glass by conduction of heat when the ballast chamber 10 is finally sealed off. Since the ballast chamber is in the form of an elongated bulb fused intermediate its ends to the float chamber, the fused joint can expand and contract slightly to prevent the float chamber wall from cracking at 15 or near the joint.

Obviously, the present invention is not limited to the particular embodiment thereof herein shown and described. Neither is it dependent upon the particular method of producing it because 20 it can be made in accordance with many other methods which will readily suggest themselves to those skilled in the art of glass working.

What is claimed is:

1. In a hydrometer of the character described 25 having a glass float chamber, a closed elongated, bulbous, ballast chamber united intermediate its ends to the lower end of the float chamber, the upper portion of said ballast chamber extending into the float chamber and decreasing in size 30 upwardly from the point of union.

2. In a hydrometer having a cylindrical, glass float chamber, a double, conical, glass, ballast chamber fused at the junction of the cones to the lower end of the float chamber on the inside

thereof and sealed to confine the ballast therein.

3. In a glass hydrometer having a cylindrical float chamber, a closed elongated, bulbous, ballast chamber composed of a single piece of glass having tapered upper and lower ends, said chamber being fused, intermediate its ends, within the lower end of the float chamber. 5

4. In a hydrometer of the character described having a float chamber, a closed ballast chamber integrally united, intermediate its ends, to the lower end of the float chamber and having a hollow, conical portion projecting upwardly 10 into the float chamber above the union.

5. A glass hydrometer comprising a cylindrical wall forming a hollow chamber, a hollow stem attached to one end of said cylindrical wall, two hollow cone-like members having their bases joined together forming a sealed chamber so that the base of each cone-like member is substantially of the same diameter as the diameter of the cylindrical wall and the junction of both cone-like members permanently fixed to the lower end of said cylindrical wall with the vertical axes 20 of both cone-like members lying in the vertical axis of the cylindrical wall, and a weight within 25 the chamber formed by said cone-like members.

6. In an article of manufacture of glass, comprising a cylindrical wall of glass, two hollow cone-like members having their bases fused together forming a sealed chamber, said bases also being fused to one end of the cylindrical wall of glass, and a liquid ballast trapped within the chamber 30 formed by said cone-like members.

GEORGE K. PORTER.
